PORTABLE TAPE PLAYER HOUSING OR SIMILAR ARTICLE

Robert S. Schreibel, Minato-ku, Tokyo, Japan, assignor to Playtape, Inc., New York, N.Y., a corporation of
New York

Filed July 18, 1966, Ser. No. 3,110

Term of patent 14 years

(Cl. D26—14)

FIG. 1 is a front, top and right side perspective view of a portable tape player housing or similar article, showing my new design;

FIG. 2 is a top plan view;

FIG. 3 is a rear elevational view; and

FIG. 4 is a left side elevational view; the right side being substantially a mirror image thereof except for omission of the tape cartridge insertion hole.

I claim:

The ornamental design for a portable tape player housing or similar article, as shown and described.
